UNITED STATES PATENT OFFICE.

JOSEPH O. BALDA, OF NEWARK, OHIO, ASSIGNOR TO A. H. HEISEY & CO., OF NEWARK,
OHIO.

DESIGN FOR A GOBLET.

59,451.

Specification for Design.

Patented Oct. 25, 1921.

Application filed April 5, 1919. Serial No. 287,839. Term of patent 14 years.

To all whom it may concern:

Be it known that I, JOSEPH O. BALDA, a citizen of Austria, residing at Newark, Ohio, have invented a new, original, and ornamental Design for Goblets, of which the following is a specification.

Figure 1 is a side elevation of goblet or similar articles showing thereon the design of the invention, and Fig. 2 is a view similar to Fig. 1 but looking at the article from a different view point.

The ornamental surface design is not confined to the specific article illustrated, as it may be applied to other articles of glassware suited to receive the ornamentation.

I claim—

The ornamental design for a goblet substantially as shown and described.

JOSEPH O. BALDA.
